UNITED STATES PATENT OFFICE.

SEYMOUR W. PEREGRINE, OF PORTLAND, MAINE, ASSIGNOR TO THE E. T. BURROWES COMPANY, OF SAME PLACE.

DOOR-CHECK.

SPECIFICATION forming part of Letters Patent No. 669,762, dated March 12, 1901.

Application filed October 27, 1900. Serial No. 34,607. (No model.)

To all whom it may concern:

Be it known that I, SEYMOUR W. PEREGRINE, a citizen of the United States, residing at Portland, in the county of Cumberland and 5 State of Maine, have invented certain new and useful Improvements in Door-Checks; and I do hereby declare the following to be a full, clear, and exact description of the invention, such as will enable others skilled in the art to 10 which it appertains to make and use the same.

This invention relates to an improvement in door-checks; and it is embodied in the construction and arrangement of parts presently to be described, and defined in the claims.

15 Heretofore many attempts have been made to secure a door-check which would permit the closing spring or power to close the door gradually, and so without the occurrence of sudden jars or stops. Such devices are desired more particularly in connection with light framework, such as screen - doors, although they are also desirable in connection with the ordinary door.

20 My invention is designed to provide a construction and device whereby the door may be moved to its various positions without requiring force to overcome a resisting power usually present in the known type of checks, such as the common form of pneumatic check 25 and closer.

A further object is to provide a device which will act promptly and gradually and, further, to avoid the use of a multiplicity of parts, joints, and toggle mechanism, all of which 30 have been used heretofore in connection with combined checks and closers.

35 My present invention is intended and designed for use as a check only, and as such is employed with other means for closing the 40 door.

While I have shown a construction and arrangement of device which has proven eminently satisfactory, yet I desire it understood that the form illustrated and presently to be 45 described is illustrated for the purpose of this specification only and not for the purpose of limitation, as various changes can be made without departing from the invention.

Figure 1 is an elevation of a section of a 50 door with the frame and check as applied. Fig. 2 is a plan view showing the door and

frame in section, and Fig. 3 is an enlarged detail view showing the relative positions of the check and frame when the door is open.

A designates the door-frame, and B the 55 door, and in this connection I prefer to employ the closing-spring C, having a connection with the upper portion of the door-frame and the outer portion of the door. These springs are at present well known in the market and largely used and are intended for the purpose of closing the door and retaining it closed. Conveniently below the spring or at any desired point is secured a cylinder D, the same having its end wall d turned at right 60 angles to form a securing-flange d', through which suitable screws are passed for securing the same to the door. The end wall is provided with the usual perforation stoppered by a regulating-screw D', having a tapered 65 side, thus forming an adjustable port for the supply and exhaust to and from the cylinder. The cylinder D is conveniently arranged at an incline, as shown in Fig. 2, and is of a sufficiently rigid construction to preserve its 70 position and shape, the same being preferably connected with the end portion in any convenient manner. The opposite end of the cylinder is open, as shown, and within the cylinder is placed the piston E, working snugly 75 therein and serving the usual purpose of drawing in air as the piston is moved outward and compressing the same as it is moved inward. The piston carries an extended rod F, the length of which is conveniently such 80 as to carry the end into engagement with the door-jamb a as the door is being closed and when closed. The outer end of the rod F is supported and passed through a standard H, having a guiding head or sleeve h at its outer 85 end, the same being arranged at a slight inclination to agree with the inclination of the cylinder, thus avoiding clamping. The rod F is designed to move freely through the sleeve h, and its end has sleeved thereon a 90 coil-spring K, one end of which is firmly secured to the rod, as at k, while the opposite end abuts against the edge of the sleeve h. The tension of the spring K is such as to force 95 the rod, with its piston-head, outward until 100 the end of the rod extends beyond the plane of the edge of the door when the latter is

open, as shown in Fig. 3. The spring also serves to assist in the retardation of the door in its closing movement, as will be apparent.

On the jamb *a* is secured a curved abutment-plate *L*, the curvature thereof being substantially on the arc of the movement of the door. This plate is conveniently secured in position by screws, and its curved end is normally projected outward, as shown.

10 To retain the rod, together with the piston, in their normal position or to prevent their disassociation, a suitable pin *f* is employed, which normally engages the sleeve *h* when the door is open and the rod forced out.

15 In operation the tension of the spring *C*, as stated, will close the door, and as the door is swinging to the end of the rod *F*, which may be conveniently shod with a round knob projection *f'*, is first brought into contact 20 with the curved outer end of the plate *L*. The rod meeting this obstruction is thereupon forced inward, compressing the spring and at the same time the air in front of the piston. The air being permitted a slow es-

25 cape through the port serves, in conjunction with the spring, to quietly resist the closing of the door; but their united strength is unequal to that of the spring *C*, which eventually draws the doors closed, thus accomplishing 30 the object desired.

In the drawings is shown the round knob or projection *f'* at the end of the rod. It might be stated that the same may be changed or varied, but that it is preferable to have a 35 curved surface at the point to avoid friction.

The object of forming the curved abutment is to preserve a uniform pressure on the rod, the same first striking the curved outer portion and gradually moving down toward the inner portion thereof as the door closes. In this 40 device it will be observed that the buffer in no wise interferes with the opening of the door owing to the fact that it is not connected with the door frame or jamb.

45 Another important advantage gained by the construction above described is that the buffing or impeding of the inward movement of the door is exerted on the jamb at the hinged edge of the door, and so at substantially right angles to the door, thus securing a result which is desirable.

Having thus described the invention, what is claimed as new, and desired to be secured by Letters Patent, is—

55 1. In a door-check, the combination with a frame and a swinging door, of a buffer comprising a reciprocating member carried by the door and independent of the frame, means for normally forcing the member toward the 60 frame, an abutment on the frame with which the reciprocating member engages during the closing and closed period of the door, substantially as described.

65 2. In a door-check, the combination with a reciprocating member and means for resisting the movement of the member in one direction

and means for moving the member in the opposite direction and an abutment-plate associated with and detached from the said reciprocating member against which the latter 70 engages as the door is closed, substantially as described.

3. In a door-check, the combination with a door and its frame, of a rod having a free end arranged on the door and adapted to engage 75 the frame, a spring for normally forcing the rod outwardly, an air-compressing cylinder, and a piston on the inner end of said rod working in said cylinder, whereby the movement of the rod is resisted in one direction 80 and the closing movement of the door checked, substantially as described.

4. In a door-check, the combination with a door, of a cylinder thereon, a reciprocating rod having a piston at one end fitted in the 85 cylinder and a free opposite end, of a spring on the rod, a support for the free end of the rod and means for preventing the escape of the rod from the cylinder, substantially as described. 90

5. In a door-check, the combination with a door and its frame, of means for closing the door and a check comprising a reciprocating member, means comprising a spring and an air-cushioning device for resisting the movement of the reciprocating member in one direction 95 and a curved abutment-plate on the frame and with which the free end of the reciprocating member engages, substantially as described. 100

6. A door-check consisting of a rod having a rounded free end, a spring sleeved on the rod, a guide for the rod against which the spring abuts, a cylinder, a piston on the rod working in the cylinder, and means for admitting air to and from the cylinder, substantially as described. 105

7. A door-check consisting of a rod having a spring sleeved thereon, a guide for the rod against which the spring abuts, a cylinder, a piston on the end of the rod working in the cylinder, in combination with a stationary curved abutment-plate independent of the rod arranged adjacent thereto, substantially as described. 115

8. The combination with a door, of a check comprising a reciprocating member secured to the side of the door and movable on a plane substantially parallel with the side of the door, means for normally moving the end of the member beyond the plane of the edge of the door, and yielding means for resisting the backward movement of the member during the closing movement of the door, substantially as described. 120

In testimony whereof I affix my signature in presence of two witnesses.

SEYMOUR W. PEREGRINE.
